LINE BLIND

Leland S. Hamer, Long Beach, Calif., assignor of
one-fourth to Paul A. Dewhirst, Los Angeles,
Calif.

Application November 23, 1945, Serial No. 630,507

11 Claims. (Cl. 133—89)

1

This invention has to do with a line blind and it is a general object of the invention to provide a simple, inexpensive, yet effective and practical line blind in the nature of an angle fitting and involving a single operating member.

The usual line blind used to close or cut off flow of fluid is connected in the line as an insert between opposed pipe sections and, furthermore, the usual line blind involves a plurality of clamping devices requiring individual operation in order to either set or release the blinding plate.

It is an object of my present invention to provide a simple yet practical and effective construction in a line blind which blind is useful in a piping system such as a manifold in the plate of an angle fitting such as an L or a T.

Another general object of my present invention is to provide a pipe line fitting of the general character referred to wherein there is a single operating member such as a hand wheel, or the like, which acts through suitable means to both clamp and release the blinding plate so that such operations can be performed easily and quickly.

A further object of my invention is to provide an improved and simplified actuating means in a fitting of the character described. By my invention I provide a simple screw means operated by a hand wheel, or the like, to move a head which in turn is coupled to a clamp member which engages the blinding plate.

Another object of my present invention is to provide a fitting of the character mentioned in which the clamp member which engages the blinding plate is of very simple construction and in which the rods which engage the clamp member to operate it are spaced in a manner to pass or accommodate the plate. The arrangement that I have provided in the present construction is such that the plate extends between the operating rods of the clamp member, the rods being spaced apart far enough to accommodate the plate.

The various objects and features of my invention will be fully understood from the following detailed description of typical preferred forms and applications of the invention, throughout which description reference is made to the accompanying drawings, in which:

Fig. 1 is a side elevation of a fitting embodying the present invention. Fig. 2 is an end view of the structure with parts of the hand wheel broken away as indicated by line 2—2 on Fig. 1. Fig. 3 is an enlarged detailed sectional view taken substantially as indicated by line 3—3 on Fig. 2.

Fig. 4 is a view similar to a portion of Fig. 3 showing a slightly modified form of construction. Fig. 5 is an enlarged detailed sectional view taken as indicated by line 5—5 on Fig. 3, and Fig. 6 is a view similar to Fig. 5 showing a modified form of construction.

The device of the present invention is generally in the nature of a pipe line fitting and is specifically concerned with a device commonly known as a line blind. The device that I have provided involves, generally, a body having a plurality of angularly related sections A and B. The sections A and B are tubular so that they form conduits or carriers for fluid and they are angularly related to fit the particular location in which the fitting is to be used. For general use it is desired to relate the sections A and B so that they are at right angles to each other, in which case the section A may be considered a transverse section while the section B may be considered a longitudinal section. In the particular form of the invention illustrated the transverse section A is open at both ends while the longitudinal section B is open only at its outer end, its inner end being joined or in communication with the section A intermediate its ends. The section A is provided at its ends with coupling means for making connection with pipe sections or the like. In the particular case illustrated coupling flanges 10 are shown at the ends of the section A. The section B is joined into or is coupled with one side of section A and projects laterally therefrom to carry the control plate C. The present invention contemplates an angle fitting wherein the sections are at any desired angle and it also contemplates that it may be in the form of an L as well as in the form shown in the drawings.

The construction that I have provided involves, in addition to the body with sections A and B and the control plate C, a clamp member D which engages the plate C to clamp it to the body of the fitting, operating means E, and connecting means F between the means E and the clamp member D.

The control plate C may, in practice, vary as do the control or blinding plates employed in fittings of the general character under consideration. In the particular case illustrated I have shown a control plate having two end portions, one a closed end portion 11 and the other an open end portion 12. The open end portion 12 has an aperture or opening 13 in it to be in communication with the fluid passage or opening 14 of the body section B when the plate portion 12 is in operating position, as shown throughout the drawings. In the particular case illustrated

the opening 13 is shown to be of the same diameter as the opening 14. However, in practice there may be a variation or difference in size between the openings. In order to center the blind in the opening 14 of the body section stops 16 are provided between the closed end portion 11 and the open end portion 12 of the control plate C.

In accordance with my invention the plate C is adapted to be clamped against a seat provided on the body of the fitting and in the particular case illustrated the outer or projecting end 15 of the body section B is finished to form the seat that receives the plate.

The clamp member D is, in effect, a continuation of the body section B and includes a body portion 30 having its inner end 31 finished to form a clamp face to oppose the plate C and having coupling means in its outer end. In the case illustrated the coupling means is in the nature of a flange 32 on the outer end of the collar 30 corresponding, generally, with the flanges 10 of the body section A. In practice, any desired form of coupling or fastening means may be used on the fitting.

In practice I provide sealing means to seal the plate with the seat 15 and the clamping face 31. Any suitable packing means may be employed to effect the desired seal. In Figs. 3 and 5 I have illustrated a sealing means involving grooves or channels 35 in the seat and clamp face to carry packing rings 36 which project or protrude in a manner to engage and seal against the sides of the plate C. In the form of the invention shown in Fig. 6 the seat 15^a is plain or without a groove and the clamp face 31^a is without a groove. However, grooves 35^a are provided in the sides of the plate to carry packing rings 36^a to engage and seal with the seat and clamping face.

The operating means that I have provided is located at the exterior of the body section A at one side thereof, preferably opposite the body section B, so that the axis of the operating means E coincides with that of the passage 14 in the body section B and the clamp member D, as shown in Fig. 3 of the drawings. Further, I prefer to locate the operating means E entirely at the exterior of the body of the fitting so that it has no parts entering or projecting into the fluid passages provided in the fitting.

The operating means E that I have provided involves a single operating member 40, a screw member 41 operated by the member 40, a head 42 operated by the screw member and a stud 43 carried by the body of the fitting and cooperating with the screw member 41.

The operating member 40 may be any suitable part to be engaged manually for turning or to be engaged by an operating tool, or the like. In practice I may make the operating member 40 in the form of a hand wheel, as shown in the drawings, so that it can be conveniently operated at any time.

The stud 43 is carried by a projection 50 provided on the exterior of the body section A opposite the body section B and projects therefrom to carry the screw member 41. In the particular construction illustrated the stud 43 is externally threaded throughout its length and its inner end is threaded into a socket 51 provided in the projection 50 and the stud is fixed to the projection by welding at 52.

The screw member 41 is operated by the member 40. In fact, it is preferably rigid with the

member 40 to turn therewith. The screw member 41 is shown as projecting from the hub portion of the hand wheel forming member 40 and it has a central threaded opening 53 receiving the projecting end portion of the stud 43. With the construction just described as the hand wheel 40 is turned the screw member 41 is rotated on the stud and is thus moved lengthwise thereof.

10 The head 42 surrounds the screw member 41 so that the screw member can rotate within it. However, the head is coupled to the screw member to move longitudinally therewith. In the particular case illustrated the head is confined between a shoulder 60 provided where the screw member 41 joins the hand wheel and a flange 61 provided on the projecting end portion of the screw member 41.

15 In practice I prefer to provide anti-friction means or bearings 62 between the head and the parts 60 and 61. It is preferred to pack or seal the bearings 62 and, therefore, I provide sealing rings 63 between the ends of the head and the parts 60 and 61.

20 In practice it is desirable to lubricate the mechanism that I have described, that is, the stud 43 and screw member 41. In the construction shown I provide a grease connection 70 at the hand wheel for introducing a suitable lubricant to the screw member 41 and the flange 61 is provided with a sleeve-like extension 71 which overhangs the projection 50 and is sealed therewith by a sealing ring 72.

25 The connecting means that I have provided couples the head 42 and the operating means E with the clamp member D so that the clamp member moves with the head. In accordance with my present invention the coupling means involves four rods 80 which connect to bosses 81

30 provided on the collar portion 30 of the clamp member D and a flange 82 provided on the head 42. I arrange the rods 80 so that they extend parallel with the axis of the body section B and the operating means E and so that two rods extend past each side of the section A in extending from the head 42 to the clamp member D. The rods are all preferably arranged as close as possible to the body section A if they extend past it.

35 However, since the bosses 81 are on the collar 30 which is at the outer side of the plate C at least two of the rods, that is, at least the pair of rods at one side of the section A must be spaced far enough apart to pass the plate C. In the particular construction that I have shown both pairs of rods, that is, the rods at each side of the section A are spaced far enough apart to pass the plate C so that the plate C can be passed into and out of position from either side of the body section.

40 The rods 80 may be attached to the bosses 81 in any suitable manner. For instance, as shown in the drawings they may be threaded at their ends to screw thread into openings provided in the bosses and, if desired, they may be shouldered at 90 as shown in Fig. 4 to seat against the bosses. In the form of the invention shown in Figs. 1, 2 and 3 of the drawings the rods have threaded end portions 91 which slidably extend through openings 92 provided in the head flange

45 93 and nuts 93 are threaded on the part 91 at each side of the flange 82. Through this construction it is possible to adjust the relationship or spacing between the flange 82 and the clamp member D and it is possible to bring the clamp member D into the desired aligned position for

proper operation. In the modified form of invention shown in Fig. 4 the threaded parts 91^a are of reduced diameter so that the rods have shoulders 95 that engage one side of the flange 82 while nuts 93^a are threaded on the portions 91^a to bear against the other side of the flange.

In accordance with my invention I preferably provided guides 96 for the rods 80 which guides may be in the nature of bosses or projections on the sides of the body section A where the rods pass, which bosses have openings 97 that slidably pass the rods. Through this construction the rods are supported for free movement lengthwise of the longitudinal section B and serve to hold the clamp member D and the head 42 of the means E against rotation and in proper alignment, and so that they too are only free to move lengthwise of the body section B.

In operating the structure that I have provided the desired end of plate C is arranged in position between the seat 15 and clamp face 31 and the hand wheel 40 is operated so that the screw member 41 is moved out on the stud 43. This moves the head 42 out or in the direction indicated by the arrow in Fig. 3. Outward movement of the head acts through the rods 80 to move the clamp member D into clamping engagement with the plate C so that the plate is tightly clamped between the member D and the end of body section B. When it is desired to release the plate to change its position or to replace it the member 40 is rotated in the opposite direction, which action causes the clamp member D to be moved away from the plate C freeing the plate so that it can be manipulated as desired.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A device of the character described including, a body having a transverse tubular section and a longitudinal tubular section projecting from one side of the transverse section, a control plate engaging the longitudinal section, a clamp member engaging the plate, operating means at the opposite side of the transverse section, and connecting means between the operating means and clamp member, the operating means including, a stud projecting from the body, a screw member threaded on the stud, a head surrounding the screw member and confined to the said screw member to move therewith axially of the stud when the screw member is rotated, and operating means for the screw member.

2. A device of the character described including, a body having a transverse section and a longitudinal section projecting from one side of the transverse section, a control plate engaging the longitudinal section, a clamp member engaging the plate, operating means at the opposite side of the transverse section, and connecting means between the operating means and clamp member, the operating means including, a stud projecting from the body, a screw member threaded on the stud, a head surrounding the screw member and confined to the said screw member to move therewith axially of the stud when the screw member is rotated, antifriction bearings between the head and screw member and operating means for the screw member.

3. A device of the character described including, a body having a transverse section and a

longitudinal section projecting from one side of the transverse section, a control plate engaging the longitudinal section, a clamp member engaging the plate, operating means at the opposite side of the transverse section, and connecting means between the operating means and clamp member, the operating means including, a stud projecting from the body, a screw member threaded on the stud, a head surrounding the screw member and confined to the said screw member to move therewith axially of the stud when the screw member is rotated, and operating means for the screw member, the head having a flange carrying the connecting means.

15 4. A device of the character described including, a body having a transverse section and a longitudinal section projecting from one side of the transverse section, a control plate engaging the longitudinal section, a clamp member engaging the plate, operating means at the opposite side of the transverse section, and connecting means between the operating means and clamp member, the operating means including, a stud projecting from the body, a screw member threaded on the stud, a head surrounding the screw member, the screw member having a flange engaging one end of the head, and an operating member for the screw member engaging the other end of the head.

20 5. A device of the character described including, a body having a transverse section and a longitudinal section projecting from one side of the transverse section, a control plate engaging the longitudinal section, a clamp member engaging the plate, operating means at the opposite side of the transverse section, and connecting means between the operating means and clamp member, the operating means including, a stud projecting from the body, a screw member threaded on the stud, a head surrounding the screw member, the screw member having a flange engaging one end of the head, an operating member for the screw member engaging the other end of the head, and sealing means between the ends of the head and the flange and operating member.

45 6. A device of the character described including, a body having a transverse section and a longitudinal section projecting from one side of the transverse section, a control plate engaging the longitudinal section, a clamp member engaging the plate, operating means at the opposite side of the transverse section, and connecting means between the operating means and clamp member, the operating means including, a stud projecting from the body, a screw member threaded on the stud, a head surrounding the screw member and confined to the said screw member to move therewith axially of the stud when the screw member is rotated, and operating means for the screw member, the screw member having an extension having sealed engagement with the body.

50 7. A device of the character described including, a flow handling body having a first elongate tubular section and a second elongate tubular section in communication with the first section and projecting from one side thereof and at right angles thereto, the second section having a seat face at its outer end, a clamp member shiftable relative to the body longitudinally of the second section and having a clamp portion opposite the said face, a flow controlling plate engaged between the seat face and said clamp

55 portion, and operating means for shifting the

said clamp member relative to the body to clamp the plate to said face including, a manually engageable member on the exterior of the body at the side thereof opposite that at which the second section is located and movable relative to the body, a threaded member carried by the body concentric with the second section and projecting from the exterior of the first section and carrying the manually engageable member, a tie member at the exterior of the body connected to the clamp member and extending therefrom to said opposite side of the first section, and means cooperatively connecting the said manually engageable member and the tie member whereby to effect clamping movement of the clamp member relative to the body.

8. A device of the character described including, a flow handling body having a first elongate tubular section and a second elongate tubular section in communication with the first section and projecting from one side thereof and at right angles thereto, the second section having a seat face at its outer end, a clamp member shiftable relative to the body and having a clamp portion opposite the said face, a flow controlling plate engaged between the seat face and said clamp portion, and operating means for shifting the said clamp member relative to the body to clamp the plate to said face including, two rigid elements, one rigid with the first section of the body, concentric with the second section and projecting from the first section at the side thereof opposite that at which the second section occurs, the other element being connected to the clamp member and extending therefrom at the exterior of the body to said opposite side of the first body section, and a single manually engageable member on the exterior of the first body section at said opposite side thereof cooperatively connecting the said rigid elements and having threaded engagement with one of them whereby operation of the manually engageable member effects clamping movement of the clamp member relative to the body.

9. A device of the character described including, a flow handling body having a first elongate tubular section and a second elongate tubular section in communication with the first section and projecting from one side thereof and at right angles thereto, the second section having a seat face at its outer end, a clamp member shiftable relative to the body and having a clamp portion opposite the said face, a flow controlling plate engaged between the seat face and said clamp portion, and operating means for shifting the said clamp member relative to the body to clamp the plate to said face including, a single manually engageable member at the exterior of the body at the side thereof opposite that at which the second section is located and movable relative to the body, a screw projecting from the exterior of the first section concentric with the second section and carrying the manually engageable member, a plurality of tie members at the exterior of the body connected to the clamp member and extending therefrom to said opposite side of the first section, guides on the exterior of the body slidably supporting the tie members for reciprocating movement lengthwise of the second section and transversely of the first

section, and means cooperatively connecting the said manually engageable member and the tie members whereby to effect clamping movement of the clamp member relative to the body.

10. A device of the character described including, a flow handling body having a first tubular section and a second tubular section in communication with the first section and projecting from one side thereof and at right angles thereto, the second section having a seat face at its outer end, a clamp member shiftable relative to the body and having a clamp portion opposite the said face, a flow controlling plate engaged between the seat face and said clamp portion, and operating means for shifting the said clamp member relative to the body to clamp the plate to said face including, a threaded part projecting from the exterior of the first section at the side opposite that at which the second section occurs, a tie member connected to the clamp member and extending therefrom at the exterior of the body to the said opposite end of the first section, and a manually operable member having threaded engagement with said part and connected with said tie member whereby operation of the manually operable member effects shifting of the tie member relative to the body and clamping movement of the clamp member relative to the said seat face.

11. A device of the character described including, a flow handling body having a first tubular section and a second tubular section in communication with the first section and projecting from one side thereof and at right angles thereto, the second section having a seat face at its outer end, a clamp member shiftable relative to the body and having a clamp portion opposite the said face, a flow controlling plate engaged between the seat face and said clamp portion, and operating means for shifting the said clamp member relative to the body to clamp the plate to said face including, a threaded part rigid with and projecting from the first section at the exterior thereof and at the side thereof opposite that at which the second section occurs, a tie member rigidly connected to the clamp member and extending therefrom at the exterior of the body to said opposite side of the first section, and a manually operable member threaded to said threaded part to shift relative to the body axially of the second section when rotated, the tie member having a part rigid therewith and engaging the manually operable member whereby the tie member is shifted relative to the body and the clamp member is operated relative to said seat when the manually operable member is rotated.
